UNITED STATES PATENT OFFICE.

MIGUEL ANGEL VILLAVICENCIO, OF CARACAS, VENEZUELA.

COFFEE-DRYING MACHINE.

Application filed June 2, 1922. Serial No. 565,468.

To all whom it may concern:

Be it known that I, MIGUEL A. VILLAVICENCIO, a citizen of Venezuela, residing at Caracas, Venezuela, South America, have ⁵ invented new and useful Improvements in Coffee-Drying Machines, of which the following is a specification.

This invention relates to apparatus for treating coffee to render it fit for use and ¹⁰ has for its object the provision of a novel power driven roaster or dryer equipped with means for forcing heated air through the coffee as it is agitated during turning movement of a containing drum.

¹⁵ An important object is the provision of a device of this character which is provided with novel bearing means for supporting the drum during its rotary movement, whereby to take the weight off of the bearings and off of the hot air conducting pipe ²⁰ through which passes the air used for effecting the drying or roasting.

Another object is the provision of a device of this character which includes only a few ²⁵ parts which are moreover so connected and arranged that they may be disassembled to permit transportation of the device in knocked-down condition in a very simple manner and even upon horse back or a mule ³⁰ pack, the device being thus advantageous for use on plantations and other places where the ordinary cumbersome roasting machines would be inconvenient.

An additional object is the provision of a ³⁵ device of this character which will be simple and inexpensive in manufacture, highly efficient in use, cheap to operate, durable in service and a general improvement in the art.

With the above and other objects and ⁴⁰ advantages in view, the invention consists in the details of construction to be hereinafter more fully described and claimed, and illustrated in the accompanying drawings, in which:

⁴⁵ Figure 1 is a side elevation of the device with parts broken away and in section,

Figure 2 is an elevation taken at right angles to Figure 1 parts broken away and in section,

⁵⁰ Figure 3 is a detail sectional view through a portion of the drum showing the baffle arrangement therein,

Figure 4 is a detail sectional view taken vertically at the axis of the drum,

Referring more particularly to the drawings the numeral 10 designates the supporting base of the machine from which rise a plurality of uprights 11 upon which are mounted bearings 12 for a shaft 13 carrying a driven pulley 15 and a drive pulley 14. ⁵⁵ This shaft also carries a worm 16 for a purpose to be described. The frame of the device further includes a cradle formed of downwardly extending semicircular bars 17 which are secured to the upper ends of certain of the uprights 11 and which are braced by inclined bars 18 connected as shown. The numeral 19 designates cross bars which are connected with the upper ends of all but one end most upright 11 and which are also ⁶⁵ connected with the upper ends of the cradle-bars 17. Mounted upon these bars 19 are bearings 20. Journaled upon the bars 17 are rollers 21 which may be of any desired size and which are arranged at spaced intervals as described.

Mounted within the cradle is a cylindrical drum designated broadly by the numeral 22 and comprising end plates 23 secured at their peripheries to re-inforcing angle bars ⁸⁰ 24 to which is secured the cylindrical shell portion 25 constituting the outer portion of the drum. This drum bears upon the rollers 21 so that the weight is borne entirely thereby instead of coming upon the bearings 20. ⁸⁵ The outside wall 25 of the drum is provided with openings 26 for the inlet of the coffee beans to be roasted or dried and associated with these openings are sliding cover plates 27 suitably mounted. The shell 25 is also ⁹⁰ provided with outlet openings 28 adapted to be covered and uncovered by sliding doors or plates 29 similarly mounted. The openings 28 and plates 29 are similar to the openings 26 and plates 27 and either may ⁹⁵ be used for placing coffee beans within the device before roasting and for removing them after the roasting is completed. The drum may be divided into any number of compartments as may be preferred so that ¹⁰⁰ different grades of coffee may be roasted at the same time and in the present instance I have shown two compartments. It should also be stated that the outer periphery of the drum is provided with perforated portions ¹⁰⁵ 30 for the escape of moisture and air from the coffee while it is being dried or roasted.

The means for effecting the heating or

roasting consists of a small furnace structure 31 having an outlet stack 32 within which is located a serpentine flue 33 into one end of which leads a pipe 34 leading 5 from a centrifugal blower 35 which has its shaft provided with a pulley 36 about which is trained a belt 37 which is, in turn, trained about the drive pulley 14. Leading from the upper end of the flue 33 is a pipe 38 which 10 connects with the center of a horizontally disposed U-shaped distributor pipe 39 which straddles the drum 22 and which has its ends leading into the center of the drum at opposite sides. The numeral 40 designates a 15 thermometer which is located in one of the arms of this distributor pipe near the point of entrance into the drum.

Each drum compartment may be subdivided by radial partitions 41 which terminate short of the distributor pipe and which have their inner ends connected by curved wire screens 42 which will permit the passage of the hot air while preventing the coffee beans from engaging the outlet ends 20 of the distributor pipe. The numeral 43 designates arcuate concentric baffles of different lengths and the numeral 44 designates a compound curved baffle which is located inwardly of the baffles 43.

In the operation of the device it will be seen that coffee beans to be roasted or dried are placed within the drum compartments through the respective feed openings 26. When the furnace is in operation and the 25 shaft 13 is driven by power applied to the pulley 15, the blower 35 will be operated and the drum will be rotated owing to the engagement of the worm 16 with a worm wheel 45 mounted upon one side of the drum. As the drum rotates the coffee beans will be shaken about and thoroughly agitated by means of the baffles 43 and 44 so that all the beans will be properly subjected to the action of the hot air which 30 enters the drum through the distributor pipe 39. The air is of course forced by the blower 35 into and through the serpentine flue 33 located within the stack, the air being subsequently forced through the pipe 38 and into the U-shaped distributor pipe 39 which discharges into the drum. After 35 circulating through the coffee the air passes out through the perforated portions 30 of the drums carrying with it whatever moisture 40 is removed from the coffee beans.

From the foregoing description and a study of the drawings it will be apparent that I have thus provided a simply constructed and consequently inexpensive machine for drying coffee in a very rapid and effective manner, very little power being necessary owing to the lightness of construction and the peculiar mounting of the drum which reduces friction to the minimum. It will be noted that the parts are

easily capable of separation so that the entire machine may be disassembled and transported from place to place wherever the use is desired, the device being thus of great utility on coffee plantations where the usual cumbersome machinery would be unsatisfactory.

While I have shown and described the preferred embodiment of the invention, it is of course to be understood that I reserve the right to make such changes in the form, construction and arrangement of parts as will not depart from the spirit of the invention or the scope of the subjoined claims.

Having thus described my invention I claim:

1. A machine of the character described comprising a supporting frame including a cradle provided with rollers, a drum rotatably supported within said cradle and provided with inlet and outlet openings, means for rotating the drum, and means for forcing a blast of hot air into the drum at the center thereof, consisting of a furnace having a stack, a blower, a serpentine flue within the furnace stack connected with the blower and a distributor pipe leading from the flue into the drum.

2. A machine of the character described comprising a supporting frame including a cradle provided with rollers, a drum rotatably supported within said cradle and provided with inlet and outlet openings, means for rotating the drum, and means for forcing a blast of hot air into the drum at the center thereof, consisting of a furnace having a stack, a blower, a serpentine flue within the furnace stack connected with the blower and a distributor pipe leading from the flue into the drum, said distributor 100 being of U-shaped and arranged in straddling relation to the drum with the ends of its arms directed toward each other and leading into the drum at its axis.

3. A machine of the character described comprising a supporting frame, arcuate bars carried by the frame and constituting a cradle, a series of rollers journaled on said arcuate bars, a drum rotatably mounted within the cradle and resting upon said 110 rollers, a worm wheel carried by the drum, a shaft journaled in said frame and provided with driving means, a worm on said shaft meshing with said worm wheel, and means for forcing a blast of hot air into the 115 drum at the center thereof.

4. In a coffee drying machine a rotary drum of cylindrical form divided into separate compartments, radially extending partitions subdividing each compartment, curved screens connecting the inner ends of the partitions, means for rotating the drum, means for forcing a blast of heated air into the drum within said screens.

5. In a coffee drying machine a rotary 130

drum of cylindrical form divided into separate compartments, radially extending partitions subdividing each compartment, curved screens connecting the inner ends of the partitions, means for rotating the drum, means for forcing a blast of heated air into the drum within said screens, a pair of concentric baffles of unequal lengths within each compartment of the drum, and a compound curved baffle located inwardly of the 10 pair of baffles.

In testimony whereof I affix my signature.

MIGUEL ANGEL VILLAVICENCIO.
